BASIN FOR MEDICAL LIQUIDS

Channing W. Gilson, Los Angeles, Calif., assignor to
American Hospital Supply Corporation, Evanston,
Ill., a corporation of Illinois

Filed Aug. 26, 1968, Ser. No. 13,278

Term of patent 14 years

Int. Cl. D24—05

U.S. Cl. D83—1

FIG. 1.

FIG. 2.

FIG. 3.

FIG. 4.

FIG. 5.

FIG. 6.

FIGURE 1 is a top plan view of the basin for medical liquids, showing my new design;

FIGURE 2 is a right side elevational view thereof, a left side elevational view being a mirror image of the right side elevational view;

FIGURE 3 is a front elevational view thereof;

FIGURE 4 is a rear elevational view thereof;

FIGURE 5 is a sectional view taken along line 5-5 of FIGURE 2; and

FIGURE 6 is a sectional view taken along line 6-6 of FIGURE 2.

I claim:

The ornamental design for a basin for medical liquids, as shown and described.
